E. J. DOOLEY

COAL DRILL

Filed May 17, 1922

Inventor:
Edward J. Dooley.

W. J. Dooley

Atty.

Patented June 3, 1924.

UNITED STATES PATENT OFFICE.

EDWARD J. DOOLEY, OF PEORIA, ILLINOIS, ASSIGNOR TO DOOLEY BROS., OF PEORIA, ILLINOIS, A CORPORATION OF ILLINOIS.

COAL DRILL.

Application filed May 17, 1922. Serial No. 561,573.

To all whom it may concern:

Be it known that I, EDWARD J. DOOLEY, a citizen of the United States, and a resident of Peoria, in the county of Peoria and State of Illinois, have invented certain new and useful Improvements in Coal Drills, of which the following is a full, clear, and exact description, reference being had to the accompanying drawing, forming part of this specification.

My invention relates primarily to one-man portable drilling outfits, preferably power operated, for use in coal and other mining operations.

One object of my invention is the elimination of the troubles heretofore experienced with machines of this nature by reason of the split nut for the thread bar.

Another object of my invention is to properly support the over-hung portion of the thread bar.

Another object of my invention is to make the thread bar reversible and provided with a driving gear which is also reversible in its position on the thread bar to the end that when the thread bar has been advanced to the limit of its travel, its position may be reversed and the parts be reassembled in starting position.

Another object of my invention is to provide a drill with a suitable motor for the operation of the thread bar and also to provide suitable angular adjustments whereby the device may be set to drill a hole at any angle within the range usually employed in this class of work.

Other objects of my invention will appear and be described in the specification.

The novelty of my invention will be hereinafter more fully set forth and specifically pointed out in the claims.

In the accompanying drawing:

Fig. 1, is a perspective view of a device embodying my invention.

Fig. 2, is an enlarged central sectional side elevation of the feeding and driving mechanism.

Fig. 3, is an end view of Fig. 2.

Fig. 4, is a side view of the thread bar

50 nut.

The same numerals of reference are used to indicate identical parts in all figures.

In its preferred form of construction my drill is mounted on the usual post 1, by 55 means of the usual chair or saddle 2, the

drill proper comprising a split boxing consisting of the lower section 3 and cap 4 between which and the lower section 3, the nut 5, is positioned, the thread bar 6 passing through the nut and carrying the drill bit 60 7. The thread bar 6 is splined as at 8 Figs. 2 and 3, and the driving gear 9 carries a key to engage the spline to rotate the thread bar. A pinion 10 is mounted on a stud 11 carried by the lower section 3 of 65 the box, and is connected by a coupling 12 to an electric or other suitable motor 13, the latter being carried by a pair of brackets 14 which are secured to lugs 15 depending from the main section 3 of the box. 70

The main section 3 of the box carries a pair of trunnions 16 which engage hooks 17 of the slide or saddle 2 and permit the drill to be swung to any angular position with relation to the post. A quadrant 18 is carried by the brackets 14 and engages a cross bar 19 carried by the slide or saddle 2 through the medium of the arms 20 which lie in the channels forming the post 1, these parts being arranged so that, by means of 80 the handle 21, the quadrant 18 may be raised and the drill tilted to the desired position and held in that position by the engagement of the quadrant 18 with the cross bar 19. Motors such as shown in the drawing are usually provided with handles one of which 22 is preferably left on the motor when it is mounted on the drill and serves as a handle for adjusting the position of the 85 drill. 90

A guide roller 23 is mounted by means of bars 24 and 25 to support the thread bar when the latter is in starting position and until it has traveled through the nut 5 to a point where sufficient of its length has 95 passed through the nut to partly counter-balance the overhang, this guide roller supporting the thread bar to reduce the wear on the nut 5 which would occur if this nut had to carry the overhung weight of the 100 thread bar.

It will be noted by referring to Figs. 2 and 4, that the nut 5 is provided with a flange 26 at each end and a lug 27 at the center of its length. The flanges 26 are 110 equal in size and form the abutment for the nut when in position in the bit. The bore of the box between the recesses for the flanges 26 is larger than the barrel of the nut between the flanges, the only contact 115

between the box and the nut being the engagement of the flanges 26 of the nut with the recesses in the box. The lug 27 engages an opening in the boss 28 of the box to prevent the nut from rotating.

The lower section 3 of the box carries a gear thrust member 29 between which and the back face of the gear 9 a ball or other suitable thrust bearing 30 is mounted to the 10 end that friction of the parts in operation may be reduced to the minimum. The pinion 10 is also provided with a thrust bearing 31.

The thread bar 6 is squared or otherwise 15 suitably shaped at each end so that the socket of the drill bit 7 may be interchangeably mounted on each end of the thread bar.

As shown more clearly in Fig. 3, the upper section 4 of the box is pivotally connected as at 32 with the main section 3, at one side of the box and is held in closed position by a key 33 which is carried between a pair of upstanding lugs 34 of the 25 lower section 3 of the box the shape of this key being better shown in Fig. 1.

The operation of the device is as follows. Assuming that the parts are in position as shown in Fig. 1, and that the post is properly mounted between the floor and roof of a mine, the operator adjusts the angle at which he desires to drill the hole by means of quadrant 18 as well as by swinging the post on its upper and lower points and 30 closes the switch to start the motor and the drill bit, the thread bar, as it rotates, feeding the bit forward until the bit has penetrated the length of the thread bar, whereupon, the motor is stopped and the key 33 35 moved to release the upper section of the box, whereupon the upper section of the box is turned upon its pivot and the thread bar, gear, and nut are raised and retracted to bring the drill bit out of the hole, whereupon the gear 9 is removed from the thread bar and placed upon the other end thereof and moved adjacent the nut, the thread bar is reversed, and a longer drill bit attached to the end opposite to that which 40 formerly carried the drill bit, and the point of the drill bit inserted in the hole to bring the nut and gear into proper position and reengagement with the box, the thread bar then resting on the guide roller 23 whereupon the upper portion 4 of the box is closed over the nut and locked by the key 33. The 45 motor is again started to rotate and advance the drill bit another thread bar length.

If it is desired to continue the drilling, the upper section of the box may be again turned back on its pivot and the gear, thread bar, and nut again raised out of engagement and reversed, and a section inserted between the drill bit and the thread bar

and the parts re-assembled for drilling the 65 hole to a further depth and so on.

By making the nut 5 solid, I am enabled to obtain the full benefit of its threads whereas, in previous constructions where the thread bar nut has been split, one half being carried on the lower portion of the box and the other half being carried on the upper portion practically all of the wear has come on the threads of the lower half because of the play between the upper and 70 lower halves of the box, these parts being usually fitted together without proper machine work and no provision being made for holding the parts in proper alignment.

By reversing the nut and thread bar, the 75 wear is equally distributed to both sides of the threads in the nut and on the thread bar.

By supporting the over hung portion of the thread bar, its weight is rendered ineffective to cause undue binding and wear on 80 the nut.

By providing the quadrant for adjusting the angular position of the drill, the alignment of the hole is maintained without subjecting the parts to undue strain.

Having thus fully described my invention, I claim.

1. In a coal drill the combination of a post, a chair mounted on the post and provided with means whereby it may be adjusted to different positions along the post, a box carried by the chair in swingable relation thereto, drilling mechanism and gearing carried by the box, a motor for driving the drilling mechanism, the motor being mounted in fixed relation to the box, and angle adjusting means cooperating between the mounting for the motor and the chair whereby the angular position of the box and the associated parts may be adjusted.

2. In a coal drill the combination of a post, a chair provided with a depending portion, a box swingably mounted on the chair, drilling mechanism and its gearing carried by the box, a motor for the drilling mechanism, a mounting for the motor carried by the box, and angle adjusting means cooperating between the mounting for the motor and the depending portion of the chair.

3. In a drill the combination of a post, a sliding chair mounted thereon and adjustable with relation thereto and comprising in part a depending portion, a box swingably mounted on the chair, drilling mechanism and its gearing carried by the box, a frame attached to the box, a motor carried by the frame for driving the drilling mechanism, a thread bar guide carried by the frame, and an angle adjusting member carried by the frame and cooperating with the depending portion of the chair.

EDWARD J. DOOLEY.
